UNITED STATES PATENT OFFICE.

JOHN EDGAR, OF ROCHESTER, MINNESOTA.

WHIFFLETREE-CENTER.

SPECIFICATION forming part of Letters Patent No. 372,365, dated November 1, 1887.

Application filed February 25, 1887. Serial No. 228,823. (No model.)

To all whom it may concern:

Be it known that I, JOHN EDGAR, of Rochester, in the county of Olmsted and State of Minnesota, have invented certain Improvements in Whiffletree and Evener Centers, of which the following is a specification.

This invention relates to means for pivoting whiffletrees or eveners to their supports. The common method of accomplishing this is to 10 pass a loose bolt through the whiffletree or evener and through the support and secure it in place by a nut on its end. This bolt soon becomes loose in its place, and the evener or whiffletree plays thereon, increasing the wear 15 of the parts, causing them to rattle, and often jarring off the nut, so that the bolt is liable to get out of place.

The object that I have in view is to provide a strong, compact, and durable joint for an 20 evener or whiffletree, that shall be free from the objections that arise from the use of a loose bolt in this position.

The invention consists, generally, in the construction and combination hereinafter described, and pointed out in the claim.

In the drawings forming a part of this specification, Figure 1 is a cross-section of a carriage or wagon pole having an evener secured thereto by my improved joint and with two whiffletrees, each secured to the evener by a similar 30 joint. Fig. 2 is a plan of the hub that is secured to the whiffletree or evener center. Fig. 3 is a vertical section through the hub and fixed axle. Fig. 4 is a similar view with the 35 parts separated. Fig. 5 is a section at right angles to the plane of Fig. 3. Fig. 6 is a vertical section through the hub and axle, showing a different means for locking the parts together.

40 In the drawings, 2 represents a portion of a carriage-pole, or it may represent any other suitable support for a whiffletree or evener.

3 represents an ordinary evener or double-tree that is secured to the pole 2.

45 4 represents ordinary whiffletrees, that are secured to the ends of the evener. This evener is secured to the pole, and the whiffletrees are each secured to the evener by my improved joint, hereinafter described.

50 5 represents an axle or stud, that is secured rigidly to the pole or other support and forms

a fixed center about which the tree has a pivoted or oscillating movement. A hub, 7, having a central bore that fits closely upon the axle 5, is secured to the tree and turns with it 55 upon the fixed axle 5.

I prefer to secure the axle rigidly to or form it integrally with a plate, 9, that can be secured to the pole or other support by bolts 19 or other suitable means.

To secure the tree in place and prevent its hub 7 from coming off the axle 5, and at the same time to form a dust or sand guard for the joint, I prefer to form the plate 9 with a vertical ring, 10, that is concentric with the axle 65 5. Near the top of this ring I provide a flange, 13, that projects toward the center. I also provide the hub 7 with a plate, 11, by which it may be secured to the tree, having a dust-ring, 12, that fits around the ring 10 on 70 the plate 9. The hub 7 is also provided with a horizontal flange, 15, below the plate 11, that is adapted to lock under the flange 13 on the ring 10.

The flange 15 does not extend entirely around 75 the hub 7, that portion that is free from the flange being brought over the flange 13. The hub can be slipped onto the axle until the flange 15 is below the flange 13, when the hub may be given a half-revolution, and the flange 80 15 will be carried under the flange 13 and the hub will be securely locked to the axle and can be removed only by reversing this movement.

In applying the device the parts will be so arranged that it will be necessary to turn the 85 evener or whiffletree so that its rear side will be in front and the hub will be brought over the axle in this position. The evener or whiffletree will then be reversed, and thereby locked in place. As it will be impossible to reverse the tree while in use, it will be seen that it cannot be removed by any accidental means.

A rubber or other packing, 17, may be placed around the axle 5, where it will be compressed by the flange 15, and will cause a close 95 fit to be made between the flanges 15 and 13. With this device the whiffletrees may be above the evener, as shown in Fig. 1, or they may be conveniently hung below the evener, thus bringing the line of draft down to the surface 100 of the pole. Another advantage is that all hammer-straps and clevises may be dispensed

with. Another advantage is that the top surfaces of both the eveners and the whiffletrees may be entirely smooth, the projecting ends of the bolts and nuts being on the under side, 5 where they are entirely out of the way.

I have shown the hub 7 locked upon the axle 5 by the flanges arranged between the plates, and I consider this the preferable arrangement, as, among other advantages, the 10 end of the axle need not extend through the wood. I do not, however, confine myself to this means for securing the hub to the fixed axle, as I may use other means for this purpose. In Fig. 6 I have shown the end of the fixed axle 15 extending through the hub and whiffletree and provided on its end with an ordinary nut. These centers may be put upon the market in-

dependently of the carriages, and be applied to any carriage by the user thereof.

I claim as my invention—

A whiffletree or evener center comprising a plate, 9, adapted to be secured to a suitable support, a projecting spindle, 5, secured rigidly to said plate, a plate, 7, adapted to be secured to the whiffletree or evener and provided with a hub fitting upon said spindle, and a locking device securing said hub upon said spindle, substantially as described.

In testimony whereof I have hereunto set my hand this 17th day of February, 1887.

JOHN EDGAR.

In presence of—

C. J. PORTER,
ARTHUR L. GORE.
